UNITED STATES PATENT OFFICE

OSWALD E. WAHLBERG, OF EVANSTON, ILLINOIS

SUPPORTING DEVICE

Application filed March 24, 1931. Serial No. 524,981.

This invention relates to certain novel improvements in supporting devices, and has for its principal object the provision of an improved construction of this character which will be highly efficient in use and economical in manufacture.

It is an object of this invention to provide an improved, convenient, and economically manufactured device for detachably supporting various articles, such, for example, as a broom, mop, brush, garden tool or other object provided with a handle, from an upright support.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a side elevational view of the invention as associated with a brush;

Fig. 2 is a sectional detail view on an enlarged scale and on the line 2-2 in Fig. 1, illustrating a preferred construction of the invention; and

Fig. 3 is a view similar to Fig. 2 but showing the manner of detaching the article, in this instance a broom, from the hook embodied in the invention.

Referring to the drawing wherein a practical embodiment of the invention is illustrated, an upright surface such, for example, as a wall, as indicated at 10, and screwed into this surface 10 is the threaded portion 11 of a screw element 12 which has a substantially S-shaped hooked end portion 13, the screw 12 carrying a guiding cap 14, if desired.

A broom is indicated at 15 and includes a handle 16 upon which the sleeve 17 of the invention is mounted in any suitable manner, as by frictional engagement, the upper end 45 of the sleeve 17 having a hole 18 formed therein as defined by the internal flange 19.

In use the portion 20 of hooked end 13 will be introduced through the hole 18 so that one end of this portion 20 will be disposed under 50 the flange 19 (Fig. 2) whereby the sleeve 17

and article 15 will be suspended in vertical position.

In removing the article 15, which may be, as has been said, a broom, brush, tool, etc., the sleeve 17 and handle 16 of the article are tilted into an angle (Fig. 3) with the surface 10 which will permit the flange 19 to be slipped off the end 20 of the hook 13, as seen in Fig. 3.

The invention thus provides a single and convenient device for supporting, in vertical position, any tool or article which has a handle upon which the sleeve 17 may be fitted either rigidly or detachably.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A device for supporting in a vertical position from an upright surface articles provided with a handle, comprising a sleeve adapted to be fitted on the said handle and having a hole in its upper end and an internal flange on the sleeve around said hole, and a screw member insertible into the surface and including a hook element insertible through said hole in such a manner that a portion of said hooked end will engage under said flange.

2. A device for supporting in a vertical position from an upright surface articles provided with a handle, comprising a sleeve adapted to be fitted on the said handle and having a hole in its upper end and an internal flange on the sleeve around said hole, and a screw member insertible into the surface and including a hook element, said hook element including an end portion extending substantially parallel to the body of said screw member and insertible through said hole in such a manner that said end portion will engage under said flange.

3. A device for supporting in a vertical position from an upright surface articles provided with a handle, comprising a member adapted to be fitted on the said handle and having a hole in its upper end and an internal flange on the member around said hole, and a screw member insertible into the surface and including a hook element, said hook element including an end portion extending substantially parallel to the body of said screw member and insertible through said hole in such a manner that said end portion will engage under said flange.

In testimony whereof I affix my signature.

OSWALD E. WAHLBERG.
